(74) *Attorney, Agent, or Firm* — Frank Niranj(57) **CLAIM**

The ornamental design for a cage as shown and described.

DESCRIPTION

FIG. 1 is a perspective view of a cage showing my new design;
 FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged front view of the encircled portion in FIG. 1;

FIG. 10 is an enlarged front view of the encircled portion in FIG. 1;

FIG. 11 is an enlarged front view of the encircled portion in FIG. 1;

FIG. 12 is an enlarged front view of the encircled portion in FIG. 1; and,

FIG. 13 is an enlarged front view of the encircled portion in FIG. 2.

The dot-dash lines define the bounds of the enlarged portion of FIG. 1 and FIG. 2, and form no part of the claim.

1 Claim, 13 Drawing Sheets(56)
